CLAIM

The ornamental design for a flexible fishing lure, as shown and described.

DESCRIPTION

FIG. 1 is a side view of a flexible fishing lure in a helical orientation in condition of use it being understood that the broken line showing of a fishing line is for illustrative purposes only and forms no part of the claimed design.

FIG. 2 is an enlarged top plan view of the flexible fishing lure of FIG. 1 in a planar orientation, the bottom view being a mirror-image thereof;

FIG. 3 is a left-side view of the flexible fishing lure of FIG. 2, the right-side view being a mirror-image thereof;

FIG. 4 is a rear view of the flexible fishing lure of FIG. 2; and,

FIG. 5 is a front view of the flexible fishing lure of FIG. 2.
